UNITED STATES PATENT OFFICE.

JAMES W. BUCKHART, OF SAN FRANCISCO, CALIFORNIA, ASSIGNOR TO PORT ORFORD CEDAR SEPARATOR COMPANY, OF SAN FRANCISCO, CALIFORNIA, A CORPORATION OF NEVADA.

BATTERY-SPACER-MAKING MACHINE.

1,404,713.

Specification of Letters Patent. Patented Jan. 24, 1922.

Application filed June 17, 1920. Serial No. 389,674.

To all whom it may concern:

Be it known that I, JAMES W. BUCKHART, a citizen of the United States, residing in the city and county of San Francisco and State 5 of California, have invented certain new and useful Improvements in Battery-Spacer-Making Machines, of which the following is a specification.

This invention relates to a wood working 10 apparatus particularly designed for forming wood battery spacers which are of relatively thin straight grain construction, and are provided with grooves or depressions permitting the circulation of the active material when 15 in use.

One of the principal objects of this invention is to provide an improved form of endless conveyor having a material supporting 20 friction surface whereby the material as operated on may be cut through without the cutters contacting with the conveyor.

A further object is to provide a novel form 25 of adjusting means for the conveyor to obtain the true running thereof.

A further object is to provide an improved 30 form of bed over which the conveyor operates, and so constructed as to permit the passing of chips or like severed material through the bed at a point beneath the passage of the conveyor therefrom.

Another object is to provide an improved 35 form and arrangement of presser feet adjacent to the cutter head whereby the material as operated by the cutter head is held firmly in contact with the conveyor friction surface.

With the above mentioned and other objects in view, the invention consists of the novel construction and combination of parts hereinafter described illustrated in the accompanying drawings, and set forth in the 40 claims hereto appended, it being understood that various changes in the form, proportion, size and minor details of construction within the scope of the claims may be resorted to without departing from the spirit or sacrificing any of the advantages of the invention.

To more fully comprehend the invention, reference is directed to the accompanying 50 drawings, wherein—

Figure 1 is a view in side elevation partly in section of the preferred embodiment of my invention.

Figure 2 is a vertical sectional view taken

on line 2—2 of Figure 1 viewed in the direction of the arrows. 55

Figure 3 is a horizontal sectional view of the conveyor truing means taken on line 3—3 of Figure 1 viewed in the direction of the arrows. 60

Figure 4 is a view similar to Figure 3 but taken on line 4—4 of Figure 1.

Figure 5 is a view in detail perspective of the cutter head and its associated knives and 65 saws operating on a strip of material in forming battery spacers therefrom.

Figure 6 is a detail view in side elevation of the presser feet at opposite sides of the cutter head.

Figure 7 is a view in rear elevation of one 70 pair of presser feet, and taken on the line 7—7 of Figure 6.

Figure 8 is a sectional view through one 75 of the presser feet taken on line 8—8 of Figure 7.

Figure 9 is a transverse sectional view 80 through one pair of presser feet taken on the line 9—9 of Figure 8.

Referring to the drawings, wherein like characters of reference designate corresponding parts throughout the several views, the numeral 1 indicates a suitable supporting frame preferably elongated in plan as illustrated in Figures 1 and 2 of the drawings, and on one face of which adjacent opposite 85 ends are provided the parallel vertically disposed table guides 2 terminating at the upper edge or top of the frame. Positioned adjacent to the front face of the frame 1, is a suitable table or bed 3, from the inner face 90 of which depends slotted legs 4, which have sliding engagement with the guides 2. The table or bed is held in its vertically adjusted position preferably with its upper edge substantially flush with the upper edge or top 95 of the frame by suitable clamping or retaining members 5 in the form of bolts which project outwardly from the guides 2, and pass through slots in the legs 4 as in Figure 1 of the drawings. The horizontal top 6 of the 100 bed or table 3 is longitudinally slotted as at 7 to provide apertures through which clips or other material severed from the body operated on may pass should the same find their way below the conveyor hereinafter 105 described.

Movable longitudinally over the surface 6 of the bed or table 3 with its inner surface in

contact with the dividing portions of the slots 7 is an endless flexible metallic conveyor 8 preferably formed of band steel, and the same operates at opposite ends of the apparatus over the periphery of a driven wheel 9 and over the periphery of a suitable supporting wheel 10. The wheels 9 and 10 are carried on axles 11 supported in brackets 12 secured to opposite ends of the frame 1, as 10 in Figures 1, 3 and 4 of the drawings.

The drive wheel 9 is rotated in the direction of the arrow Figure 1 by power applied to the gear 13 through a driving pinion 14 carried by a shaft 15, and which shaft is in 15 turn rotated by power transmitted thereto through a band wheel 16.

The supporting wheel 10 is capable of adjustment to and from the driven wheel 9 to compensate for stretch in the endless 20 conveyor 8 and the shaft 11 mounting said supporting wheel 10 is also capable of adjustment to vary the angle of the periphery thereof relative to the periphery of the driven wheel 9 to compensate for any unevenness in the opposite sides of the conveyor 8, and to accomplish these results the 25 following mechanism is employed. The frame 12 cooperating with the supporting wheel 10 carries the bearing blocks 17 adjustable in guides 18, and from these bearing blocks extend the adjusting screws 19 which pass through openings in the outer 30 ends of the associated frame 12. The members 19 are capable of adjustment within 35 their guides through the operation of nuts 20 threaded thereon and bearing against the ends of the frame 12 adjacent the portions thereof through which the members 19 pass.

Suitable idler rollers 21 are positioned at 40 opposite ends of the bed or table 3 with their upper surface approximately flush with the upper surface of the bed or table, as in Figure 1 of the drawings. The rollers 21 support that portion of the endless conveyor 8 travelling over the surface of the bed or table 3 preventing the undue flexing of the conveyor as it enters on or leaves the ends of the table. The parallel side edges of the conveyor 8 are guided over and longitudinally of the upper surface of the table 3 by 45 suitable guide flanges 22 secured to the surface 6 of the bed or table 3 with the inner portions thereof slightly overlying the opposite side edges of the conveyor 8, as in Figures 2, 7 and 9 of the drawings; the guides being secured in position by suitable screws 50 23. The flanges of the guides 22 overlying the side edges of the conveyor 8 retain the conveyor in slight frictional contact with 55 the dividing walls separating the walls 7, as in Figure 9 of the drawings, insuring the uniform guiding of the conveyor over the table and the maintaining of the same in contact therewith. Vulcanized, cemented, or otherwise secured to the outer face 65

of the metallic conveyor 8 is a suitable composition or fabric friction surface 24 of a width slightly less than that of the metallic conveyor 8, and also of a width less than the distance between the flanges of the 70 guides 22, as in Figures 2, 7 and 9 of the drawings, providing a space 25 above the surface of the conveyor 8 and between the inner edges of the flanged guides and the outer edge of the surface 24 for the reception of cutting members hereinafter described.

The material to be operated on, which is in the form of a relatively thin flat short lengthed strip of wood of a thickness 80 slightly greater than the usual veneer is deposited on the friction surface 24 either by hand or otherwise at a point on the friction surface where the same is received on the feed end of the bed or table, and said material is guided between suitable material guides 26 raised on the guide flanges 22, and is of a width to overlie the friction surface 24, as in Figures 2, 7 and 9 of the drawings. During its movement longitudinally 90 of the bed or table 3 on the friction surface 24, the material passes between suitable compression or feed rolls 27 arranged in pairs, and certain of the rolls being positioned beneath the upper surface 6 of the table and 95 disposed transversely thereof to contact with the end faces of the endless conveyor 8 and certain other rollers of each pair being disposed immediatley above the first mentioned rolls and carried by a suitable pivoted compression frame 28. The frame 28 is connected at the opposite sides of the apparatus through links 29 with fixed supports 30, and said frame is normally pressed downwardly to force the rolls carried thereby toward the friction surface 24 by a lever 31 carrying an adjustable weight 32 at the free end thereof. The adjustment of the weight 32 on the lever 31 regulates the tension placed on the feed rolls carried by the 100 frame 28.

Adjacent to the discharge end of the surface 6 of the bed or table 3, and extending transversely therefrom, is a suitable cylindrical cutter head 34 mounted in bearings 115 35 associated with the upper ends of adjustable brackets 36 capable of being raised and lowered relatively to the surface 6 of the table 3, through the adjustment of clamping members 37.

For forming the particular battery spacer illustrated the cutter head 34 carries at spaced intervals around its periphery suitable radially disposed cutter knives 38 arranged in parallel spaced relation longitudinally of the cutter head, as in Figure 5 of the drawings, and at the opposite ends of said cutter knives 38 are located the trimmer knives 39, the points of which are in alignment and project slightly beyond the 125 130 outer face of the cutter head.

aligned points of the cutter knives 38, said trimmer knives adapted on the rotation of the cutter head to project slightly into the space 25 on opposite sides of the friction surface 24, as illustrated in Figure 5, trimming or cutting the side edges of the material to be operated on to provide a body of a given width. Adjacent to said trimming knives 39, and disposed flush with the inner faces thereof are positioned suitable trimmer saws 40, the teeth of which project below the foot of the trimmer knives 39, as in Figure 5 of the drawings, to cut overhanging material carried by the main body 15 on a line approximately parallel with the side edges of the friction surface 24 and insuring a smooth edge at opposite sides of the material acted on.

From an examination of Figure 5 of the drawings, it will be observed that the cutter knives 38 arranged with their points in alignment, and slightly in rear of the points of the trimmer knives 39 will groove or channel the upper surface of the material 25 acted on, while the trimmer knives 39 and saws 40 will cut the material to a given width and provide a smooth side edge therefor. Extending transversely of the cutter head 34 between the rows of teeth 38, 39 30 and saws 40 are suitable surfacing knives 41 for finishing the upper surface of the material as the same is channeled and trimmed. Any suitable means may be employed for rotating the cutter head in the direction of the arrow, Figure 6 of the drawings.

To retain the material tightly in contact with the friction surface 24 of the conveyor 8, while the same is being operated on, I 40 prefer to employ suitable presser feet arranged in pairs at opposite sides of the cutter head 34, as illustrated in Figures 1 and 6 of the drawings, and each pair of presser feet being identical, except being arranged 45 with their toes pointing toward each other at opposite sides of the cutter head, the description of one pair is thought will suffice.

Secured to opposite sides of the table 3, at opposite sides of the cutter head 34, are 50 the presser feet supporting frames 42, in the form of an inverted U, and within each of which is mounted a pair of presser feet 43. Each presser foot has extended from the lower edge thereof adjacent the cutter head 34, a toe 43, and in rear of this toe 43, each foot is provided with a chamber 44. A shaft 45 connected at its opposite ends to the opposite sides of the U-frame 42 passes through the lower portion of each 55 presser foot near the point of extension of the toe therefrom, and provides a fulcrum on which said presser feet of each pair are pivotally mounted to swing on a horizontal axis. To normally maintain the toes 43 of 60 the respective presser feet forced down-

wardly, I employ a compressed spring 46 coiled about a guide bolt 47, which is threaded into a flange 48 on the upper rear edge of each presser foot 43. The bolt 47 passes through a guide opening 49 in the body portion of the U frame 42 and between its head and its point of passing through the frame 42, I position the aforesaid spring 46. The action of the spring is to draw the rear upper end of each foot toward the cutter head 34, depressing the toe, as in Figure 8 of the drawings. The contact of the flange 48 with the rear surface of the body of the member 42 limits the pivotal movement of the toes 43 downwardly, and a suitable adjusting screw 50 carried by a flange 51 at the forward upper edge of the respective presser feet contacts at its free end with one face of the body of the member 42 and limits the upper pivotal movement of the respective toes 43.

Mounted in the respective chambers of the presser feet 43 are suitable compression rolls 52 carried on a shaft 53 mounted in a floating bearing 54 movable vertically in 90 a vertically disposed guide slot 55 formed in the opposite side walls of each presser foot. The compression rolls 52 are normally forced downwardly toward the conveyor by suitable coil springs 56 positioned 95 between the floating bearings 54 and the upper ends of the slots 55, said springs being held within the slots by guide screws 57. It will be apparent that the pivoted action of the respective presser feet on their 100 fulcrums 45 does not in any manner affect the position of the presser rolls 52 on the material acted on, or on the friction surface 24 of the conveyor, inasmuch as said presser rolls 52 are free to move independently on their floating fulcrum relatively to the presser feet. The lower surface of each presser foot is slightly inclined downwardly from the heel to the toe, as at 58, insuring an easy sliding of the material beneath the 110 same as it is carried by the friction surface 24 of the conveyor 8 to within the path of the cutter head 34 or from the path of the cutter head 34. The toes of the pair of presser feet adjacent to the discharge end 115 of the table, and to receive the material after it has been acted on by the cutter head 34 are upwardly beveled, as at 59, to insure the easy sliding of the material beneath said pair of presser feet after it is conveyed beneath the cutter head 34.

By the employment of the presser feet 43 above described, and arranged as illustrated in the drawings, it will be apparent that the material as operated on by the 125 cutter head 34 is firmly held to the upper surface of the friction material 24 by the action of the presser feet, and it will also be apparent that, by the forcing of that portion of each presser foot nearest the cut- 130

ter head downwardly onto the material adjacent its point of operation by the cutter head, the material nearest its point of being operated on is held under increased pressure with the friction surface 24.

5 By providing the compression rolls 52, it will be apparent that the portion of the material which has been fed past the toe 43 of the respective presser feet is held in tight 10 contact with the friction material 24.

15 While but a single trimmer knife 41 is illustrated in the drawings, and is positioned between adjacent rows of cutter and trimmer knives, it is to be understood that any 20 number of surfacing knives 41, and any number of cutting and trimming knives can be employed just so long as the same are arranged longitudinally of the circumference 25 of the cutter head 34.

20 By providing the trimmer saws 40 adjacent the inside wall of each trimmer knife 39, it will be apparent that the material is partly severed from the main body by the saw 44 prior to being chipped or removed 25 therefrom by the knife 39.

I claim:—

1. In a machine for the described purpose, the combination with a frame, a bed or table supported thereon, an endless unbroken metallic conveyor operating over 30 said bed in contact therewith, a pair of guide flanges overlying the opposite side edges of said conveyor at its point of travel over said bed, a friction surface on said conveyor of 35 a width less than that of the conveyor and less than the distance between said flanges, a cutter head disposed transversely of said conveyor above said bed and provided with a pair of trimmer knives for reception in 40 the space between the flanges over the opposite sides of said friction surface and falling short of contact with the metallic conveyor, means for pressing the material to be operated on into contact with said friction surface at a point adjacent to the operative field of said trimmer knives, means for 45 rotating the said cutter head, and means for operating said conveyor in a direction toward the direction of rotation of said cutter head.

50 2. In a machine for the described purpose, the combination of a frame, a slotted bed mounted thereon, an endless unbroken metallic band conveyor operating over said bed 55 with its under surface in contact therewith, a pair of guide flanges carried by said bed and overlying the opposite side edges of said conveyor, a friction surface carried by the outer face of said conveyor between its 60 opposite side edges and disposed to lie in spaced relation with the inner edges of said flanges, a trimmer knife, a cutter for extending into the space between the edges of said friction surface and the said flanges and 65 falling short of contact with the upper sur-

face of said metallic conveyor, means for operating said conveyor, and means for operating said trimmer knife and cutter to act on the material conveyed.

3. In a machine for the described purpose, 70 the combination of a frame, a slotted bed mounted thereon, an endless unbroken metallic band conveyor operating over said bed with its under surface in contact therewith, a pair of guide flanges carried by said 75 bed and overlying the opposite side edges of said conveyor, a friction surface carried by the outer face of said conveyor between its opposite side edges and disposed to lie in spaced relation with the inner edges of said flanges, a rotary cutter head extending transversely over the bed, a pair of trimmer knives carried at opposite ends of said cutter head for projecting into the space on said conveyor between said friction surface and 80 flange edges, a plurality of channeling cutters carried by said head between said trimmer knives and disposed with their cutting edges falling short of the path of travel of said conveyor, means for rotating said cutter 85 head, means adjacent said cutter head for maintaining the material to be operated on in contact with said friction surface, and means for operating said conveyor in a direction toward the direction of rotation of 90 said cutter head.

4. In a machine for the described purpose, the combination of a bed or table, an endless, unbroken, flexible metallic band conveyor operating thereover in contact therewith, a driven band wheel around which one end of said conveyor passes, a supporting band wheel around which the other end of said conveyor passes, means for adjusting one of said band wheels relatively to the 100 other to regulate the tension of said conveyor, a non-metallic friction surface carried by the outer face of said conveyor, and a cutter head extending transversely of said conveyor and friction surface for 105 operating on the material as conveyed by said conveyor and friction surface.

5. In a machine for the described purpose, the combination with an endless unbroken flexible metallic conveyor operating 115 a pair of band wheels around which said belt operates and dividing the same into upper and lower flights, a bed over and in contact with which the upper flight of said conveyor belt moves, a non-metallic friction surface carried by the outer face of said belt, a rotatable cutter head extending transversely over said bed above said friction surface for operating the material deposited and conveyed by said friction surface, and means 120 for varying the plane of the periphery of one of said band wheels to compensate for stretch at opposite sides of said conveyor.

6. In a machine for the described purpose, the combination of a bed or table, an endless, 130

- unbroken, flexible metallic band conveyor operating thereover in contact therewith, a driven band wheel around which one end of said conveyor passes, a supporting band 5 wheel around which the other end of said conveyor passes, means for regulating the tension of said conveyor, a non-metallic friction surface carried by the outer face of said conveyor, and a cutter head extending 10 transversely of said conveyor and friction surface for operating on the material as conveyed by said conveyor and friction surface.
7. A machine for the forming of battery 15 spacers from short lengths of veneer-like, wooden sheets, comprising a bed or table, an endless unbroken flexible metallic band conveyor operating thereover with one surface in contact with the surface of the bed or 20 table, a pair of band wheels of relatively large diameter, one positioned adjacent each end of the bed or table and around which said conveyor passes, means for controlling the tension of the conveyor, means for driving one of said band wheels to move the 25 conveyor relatively to the table, a cutter head extending transversely of the conveyor for operating on the material as conveyed thereto by the movement of said band conveyor and a presser member for acting on 30 the material at opposite sides of the cutter head for forcing the material into frictional contact with the conveyor and the conveyor into frictional contact with the bed or table whereby an unyielding uniform surface is 35 provided for supporting the material as acted on by said cutter.

In testimony whereof I have signed my name to this specification.

JAMES W. BUCKHART.
